(57) **CLAIM**

The ornamental design for a light pole, as shown and described.

DESCRIPTION

FIG. 1 is a top, front and right side perspective view of a light pole showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of portion 8 in FIG. 1; and,

FIG. 9 is an enlarged view of portion 9 in FIG. 1.

The light pole is shown with symbolic breaks in its length. The appearance of any portion of the article between the break lines forms no part of the claimed design.

The broken lines represent the boundaries of the enlarged views and form no part of the claimed design.
